FERNAND E. D'HUMY, OF ENGLEWOOD, NEW JERSEY.

AIRSHIP.

Application filed November 18, 1925. Serial No. 69,833.

This invention relates to airships and one of its objects is to simplify and strengthen the structure of airships of the dirigible type and to reduce the cost of their construction.

Another object of the invention is to provide an airship having a resilient frame structure which is adapted to yield under the stress of very strong wind pressure without breakage or permanent distortion of the frame parts.

A further object of the invention is to provide an airship structure wherein a stress in any direction tending to distort or disrupt the structure will be resisted by yieldable tension members.

An airship constructed in accordance with this invention is preferably provided with a central longitudinally extending compression member which is rigid to resist compression strains but which has a limited lateral flexibility and resilience. This central compression member is surrounded by annular compression members which are so constructed that they have a limited lateral resilience and flexibility and are rigid to resist strains tending to contract them and force them inwardly toward the central compression members. These two compression members are connected together by transverse tension members, said tension members holding the annular compression members and the longitudinally extending compression member properly spaced apart and positioned in the ship structure. All of the tension members are yieldable under a strain just below their breaking strength and exerted in a direction tending to elongate said tension members.

40 In the drawings:

Fig. 1 is a longitudinal section through my improved airship;

Fig. 2 a transverse section taken substantially on the line 2—2 of Fig. 1;

45 Fig. 3 a side view of a portion of the frame structure of the airship;

Fig. 4 a transverse section taken on the line 4—4 of Fig. 1;

50 Fig. 5 an enlarged sectional view of one of the joints in the central shaft of the airship and the adjacent frame parts;

Fig. 6 a transverse section taken on the line 6—6 of Fig. 5;

55 Fig. 7 a detail plan view of a portion of the frame structure shown in Fig. 5;

Fig. 8 a detail plan view of one of the joints in the frame structure;

Fig. 9 a section taken on the line 9—9 of Fig. 8;

Fig. 10 a section taken on the line 10—10 of Fig. 9;

Fig. 11 a detail view of one of the gas bags removed from the frame;

Fig. 12 a longitudinal section showing a portion of an airship of modified structure;

Fig. 13 a transverse section taken substantially on the line 13—13 of Fig. 12;

Fig. 14 a view similar to Fig. 13 showing the central portion of the frame structure, with the radial wires omitted;

Fig. 15 a side view showing the outer envelope of the ship;

Fig. 16 a fragmentary sectional view of the envelope; and

Fig. 17 a similar view of a modified form of envelope.

The airship structure includes a longitudinal central beam or shaft S which extends throughout the length of the ship and constitutes a longitudinally extending compression member of a truss which extends throughout the length of the ship. The shaft S is formed of a plurality of straight tubular sections arranged end to end and in axial alignment in a longitudinal series. These shaft sections are numbered 1 to 8 inclusive. The opposed ends of the different sections are closed and are formed with outwardly extending flanges 9. One of said ends is formed with a concave surface 10 and the opposed end of the next adjacent section is formed with a convex surface 11 adapted to enter said concavity. Interposed between the surfaces 10 and 11 is a felt disc or cushioning gasket 12. The opposed ends of the sections are joined together by a series of bolts 13 which pass through the flanges 9 of the opposed ends. The bolts 13 serve also to secure a circular ring or hub collar 14 to the face of one of the end flanges 9. This collar serves as an anchorage for certain of the frame parts to be described later. The bolts project beyond the flange 9 of the opposed section and have nuts 15 threaded upon them. Interposed between said flange and the nuts 15 are strong coiled compression springs 16 which encircle the bolts 13.

The opposed end faces 10 and 11 are held pressed firmly toward each other and against the disc 12 by these springs 16. The bolt 110

holes in one of the flanges 9 are enlarged as at 17 to permit of lateral movement of the bolts therein. Thus a slightly flexible and resilient joint structure is provided between 5 the sections. This joint structure is duplicated between each pair of opposed sections throughout the length of the shaft. The tubular shaft sections are made of thin metal and are completely filled with a light weight 10 filler such as a specially prepared wood pulp compounded to resist compression. This filler adds compression strength to the shaft and will resist a strain tending to buckle the shaft or the sections thereof.

15 Encircling the central shaft S are a plurality of rings or hoops H. These hoops are disposed concentrically with the shaft and are arranged therealong in equally spaced positions and in substantially the same 20 transverse planes with the joints between the shaft sections. The hoops are snugly enclosed by the outer envelope 18 of the ship and their diameters are varied to give the proper taper to the ship. Each hoop is formed of a series of curved tubular sections 19 of equal length disposed end to end. These tubular sections are formed of thin metal and are completely filled with wood 25 pulp or other suitable material to strengthen them. The sections 19 are formed at their opposed or meeting ends with wide compression shoes 20 which extend out at opposite sides of the hoop. The shoe at one end of each section is formed with a convex surface 21 which is opposed to a concave surface 22 formed in the opposed shoe of the next adjacent section. Interposed between the surfaces 21 and 22 is a cushioning gasket 23 formed of a strip of felt. Each pair 30 of opposed shoes are joined together by a pair of bolts 24 which extend through the outer ends of the shoes and have nuts 25 threaded upon them. A strong coiled compression spring 26 encircles each bolt 24 35 between the nut 25 and one of the shoes 20. The springs 26 are adapted to hold the opposed shoes firmly pressed against the compression gasket 23. The opposed surfaces 21 and 22 are curved transversely of the 40 shoes 20 and the bolt apertures in one of the shoes are enlarged as at 27. Thus a slightly flexible and resilient joint structure is provided between each hoop section and the hoops are rendered resilient transversely of 45 the ship structure. Each hoop section has a limited independent resilient connection to permit a limited independent movement toward the center under an unusual and unbalanced pressure. These hoops are 50 compression members and resist strains tending to force them inwardly toward the shaft. When the hoops are assembled and properly tensioned they form compression members 55 which resist all stresses tending to contract 60 them.

A series of wire tension strands 28 extend from each hub collar 14 radially outward toward the hoop H which encircles said collar. The strands are equally spaced in a series extending around the collar and 70 their inner ends are looped and directly connected as at 29 with apertured ears formed upon the outer edge of the hub collar. The outer ends of the strands 28 are connected to coiled tension springs 30 which are in turn connected with the inner side of the hoop at equally spaced points around its circumference. The springs 30 are anchored to the hoop by means of sectional 75 clips 31 which embrace the hoop and are 80 clamped thereto by bolts 32.

A pair of opposed anchor rings 33 encircle each hub collar 14 and are disposed concentric with it. The radial strands 28 of each series are arranged in the same plane and the opposed rings 33 are disposed at opposite sides of the series of strands. The rings 33 are held in place upon the strands 28 by a series of bolts 34 which clamp the rings to opposite sides of the strands. The strands pass between a pair of felt cushioning gaskets 35 interposed between the opposed faces of the rings 33 and the strands. Leading from each ring 33 to the hub collar 14, located at the next adjacent shaft joint, 85 is a series of diagonal tension strands 36 formed of wire. These strands lead from points equally spaced around the rings 33 and connect to points equally spaced upon and around the hub collars the next adjacent shaft joints at opposite sides of the rings. The diagonal strands 36 therefore cross at points substantially midway the 90 length of each shaft section. The inner ends of the diagonal strands are looped and directly connected as at 36' to ears formed upon the outer edges of the hub collars. At their outer ends the strands 36 are connected to strong coiled tension springs 37 which are 95 in turn connected as at 38 to apertured ears formed upon the inner edges of the rings 33. The rings 33 surrounding the joint between the front shaft sections 7 and 8 are 100 connected with the front end of the shaft by 105 the strands 36 and springs 37.

Each ring or hoop H is connected to the next adjacent hoop by longitudinal tension strands 39 formed of wire. The wire strands 39 connect the different hoops at points 110 equally spaced around them. Each strand is looped and directly connected at one end, as at 40, to an outwardly extending ear formed upon one of the U-shaped clips 31. At its opposite end the strand is connected 115 to a strong coiled tension spring 41. The spring 41 is in turn connected to the clip 31 upon the next adjacent hoop. Strands 39 also lead from the outermost hoops to the front and rear ends respectively of the central shaft S. These end strands converge in- 120 125 130

wardly and are connected to the springs 41 which are in turn connected to the shaft ends in any suitable manner.

Surrounding the shaft S and spaced there-
5 along throughout its length are a plurality
of gas bags 42. These bags are curved to
describe the greater portion of a circle, a gap
43 being left between the closed ends of the
bags. Fig. 11 shows one of the bags separat-
10 ed from the frame structure of the ship.
The bag located at the front end of the
ship is formed to fill the tapering space de-
fined by the radial strands 28 and the con-
verging strands 36 and 39. The bag at the
15 stern is formed to fill the space defined by
the strands 39 and 36 and the shaft S. The
intermediate bags fill the spaces between the
hoops defined by the longitudinal outer
strands 39, the diagonal inner strands 36
20 and the radial hoop strands 28. The gaps
43 of the bags are arranged in longitudinal
alinement to provide a corridor space extending
throughout the length of the ship below
the shaft.

25 The frame structure described is adapted to maintain the shape of the airship under normal conditions but is adapted to yield resiliently under the impact of a powerful wind force upon the outer envelope and thus
30 prevent the permanent distortion or rupture of the frame. When the undue pressure is relieved, the various frame parts resume their normal shapes and positions. The radial strands 28 and their connected springs,
35 extending between the hub collars 14 and the hoop sections, exert an inward tension which tends to contract the hoop and thereby hold its sections yieldingly together under end-
wise compression. Under the stress of a
40 strong lateral impact the hoop sections are adapted to flex resiliently at the joints and to be slightly distorted to cushion the blow. The longitudinal tension strands 39 connect the series of hoops together throughout the
45 length of the ship and the springs connected to the hoops permit them to yield resiliently to an endwise force tending to displace them. The radial tension strands 28 yieldingly support the central shaft S properly cen-
50 tered within the hoops, and the diagonal strands 36, and their connected springs yieldingly hold the shaft sections in aline-
ment. These diagonal strands 36 and their springs exert a pull both longitudinally and
55 laterally outward at the shaft joints and are arranged to hold the shaft sections together end to end in series, under compres-
sion throughout the length of the shaft and are adapted also to resist buckling of the
60 shaft. Under a strong wind force tending to break the ship in two, the springs in the strands 36 and the flexible shaft joints permit the shaft to bend resiliently and cushion the blow. The ship structure is therefore
65 adapted to cushion a blow received from any

direction and to right itself when the pres-
sure is relieved.

In Figs. 12, 13 and 14 a slight modification of the frame structure is shown. In this form the shaft S, the hoops H and the 70 arrangement of the radial strands 28 and the longitudinal strands 39 remain the same as the form just described, but the diagonal strands 36^a are differently arranged from strands 36. The strands 36^a, instead of lead-
75 ing from the hub collars to the anchor rings 33 as do the strands 36, in this case lead from one pair of rings 33, across the shaft to the next adjacent pair of rings. These strands are arranged in pairs, spaced angularly around the rings 33, and the strands of each pair extend in parallel directions across opposite sides of the shaft S. This arrangement permits the gas bags to fit more closely to the central shaft and therefore 80 accommodate large bags which give greater buoyancy to the ship. Fig. 14 shows in detail the arrangement of the pairs of diagonal wires.

90 In both forms of the invention the various tension strands are shown as single wires in order to simplify the illustration. These single strands may be replaced by groups of strands of a number sufficient to give the necessary strength. Cable strands may also be used in place of wire. The tension springs in the various strands are made very strong so that under normal condition they will remain nearly contracted. For the purpose of adjusting the tension of the various tension strands turnbuckles may be introduced between the tension springs and the strands or at any other convenient place, as indicated at 44 in Fig. 5. The resistance of 95 said springs is, however, well under the maximum tensile strength of the strands so that they will yield under an unusual stress, and prevent the strands from breaking. The control means for the airship is not shown. A suspended car C is, however, indicated in 100 Fig. 1 in order to show that it may be supported by the hoops H. While I have shown the airship as round in cross section it will be understood that it may be given 105 other desired cross sectional forms by using differently shaped hoop members.

110 The outer envelope 18 of the airship is so formed as to permit it to stretch without tearing when the frame structure is distorted and to adapt it to snugly engage the frame at all times. To this end the envelope is folded back upon itself at points spaced along its length as indicated at 45 in Figs. 115 15 and 16. These folds 45 overlap longitudinally of the envelope and extend entirely around it to render the envelope extensible. The extension of the envelope is yieldably resisted by a series of coiled tension springs 120 46 and 47, arranged respectively within and without the envelope at opposite sides of 125 130

the folds 45. These springs are arranged in spaced positions around the envelope and connect at one end to anchor strips 48 stitched along the creases of the folds 45, 5 and at their opposite ends to anchor strips 49 stitched to the envelope and extending therearound at points spaced from opposite sides of the folds. The springs 46 and 47 yieldably resist an extension of the envelope 10 at the folds when the resilient frame structure becomes distorted, and when the distorting stress is relieved and the frame rights itself the springs will contract the envelope into snug engagement with the 15 frame.

In Fig. 17 is shown a portion of a modified form of envelope. This envelope is formed of sections which overlap at the edges as indicated at 50 and extend around the envelope. The extension of the envelope is resisted by tension springs in the same manner as in the form previously described. The tension springs connect directly to the overlapped edges of the envelope sections.

25. What I claim is:

1. An airship structure comprising a longitudinally extending compression member; a plurality of annular compression members encircling said longitudinal compression member and spaced along it; transverse tension members yieldably supporting the longitudinal compression member within the said annular members; and longitudinally extending tension members connecting the annular members to each other and to the ends of the longitudinally extending compression member, the said longitudinally extending tension members being connected to the annular members at points spaced 40 therearound and being longitudinally resilient.

2. An airship structure comprising a longitudinally extending compression member; a plurality of annular compression members encircling said longitudinal compression member and spaced therealong; a plurality of transverse tension members connecting each annular member at points spaced therearound to the longitudinally extending compression member and adapted to support the said member within the annular members, said transverse tension members tending to contract the annular members; inner longitudinal tension members connected to the longitudinal compression member at points spaced around it and adapted to exert a stress upon the said compression member tending to compress it longitudinally; and outer longitudinal tension members connecting the annular members to each other and to the ends of the longitudinal compression member, said outer tension members being connected to the annular members at points spaced around them.

3. An airship structure comprising a lon-

gitudinally extending compression member; a plurality of annular compression members encircling said longitudinal compression member and spaced therealong; a plurality of transverse tension members connecting each annular member at points spaced therearound to the longitudinally extending compression member and adapted to support the said member within the annular member, said transverse tension members tending to contract the annular members; inner longitudinal-tension members connected to the transverse members at points spaced around the longitudinal compression member and arranged at oblique angles to said longitudinal compression members and adapted to exert a stress upon the longitudinal compression member tending to compress it longitudinally; and outer longitudinal tension members connecting the annular members to each other and to the ends of the longitudinal compression member, said outer tension members being connected to the annular members at points spaced around them.

4. An airship frame comprising a longitudinal compression member formed of a plurality of sections arranged end to end and rigid to resist longitudinal compression strains; means flexibly connecting said sections together to permit a slight yielding under lateral or side-wise strains; a structure surrounding said longitudinal compression member and adapted to hold the outer envelope of the airship distended; and longitudinally resilient tension members arranged around the longitudinal compression member and connecting each section thereof to said surrounding structure, said tension members being adapted to exert a tension upon the longitudinal compression member both longitudinally and outwardly at all sides tending to hold the said compression member sections together and to resist bending of the longitudinal compression member.

5. An airship structure comprising a central longitudinally extending compression member surrounded by and maintained in axial alignment by longitudinally extending tension members connected thereto; a series of annular compression members surrounding the longitudinally extending compression member; a series of transverse tension members connected to the central compression member and to each of the annular compression members; and longitudinally extending tension members connecting together the annular compression members and the two ends of the longitudinally extending compression member.

6. An airship structure comprising a longitudinal central shaft formed of sections arranged end to end; means forming flexible joint connections between the shaft sections; a plurality of hoop members spaced along

- said shaft and encircling said joint connections, said hoop members being each formed of a plurality of sections arranged end to end; means forming flexible joint connections between said hoop sections; a series of longitudinally resilient tension members arranged radially around each joint connection and connecting it to the encircling hoop; longitudinally resilient tension members arranged around the shaft and extending diagonally outwardly therefrom and connecting each shaft joint with the said radial strands leading from the next adjacent joints at either side; and longitudinally resilient tension strands arranged longitudinally and connecting the different hoop members to each other and to the shaft ends, said longitudinal strands being connected to the hoop members at points spaced around them. 70
- 10 7. An airship structure comprising a longitudinal shaft formed of sections arranged end to end; means forming flexible joint connections between the shaft sections; a plurality of resiliently flexible hoop members spaced along said shaft and encircling said joint connections; means forming flexible joint connections between said hoop sections; a series of longitudinally resilient tension members arranged around the shaft and connecting it to the encircling hoop member at points spaced around said member; and longitudinally resilient tension members arranged longitudinally and connecting the different hoop members to each other and to the shaft ends, said longitudinal members being connected to the hoop members at points spaced around them. 80
- 15 8. An airship structure comprising a laterally resilient flexible longitudinal shaft; a plurality of laterally resilient flexible hoop members encircling the shaft and spaced therealong; resilient tension members extending between each hoop and the shaft and supporting the shaft within the hoops; and means resiliently holding the peripheries of the hoop members in spaced positions longitudinally of the shaft. 90
- 20 9. An airship structure comprising a laterally resilient flexible longitudinal shaft; a plurality of laterally resilient flexible hoop members encircling the shaft and spaced therealong; resilient tension members extending between each hoop member and the shaft and supporting the shaft within the hoop members; and resilient tension members arranged longitudinally of the airship structure and connecting the peripheries of the hoop members to each other, at points spaced therearound, and to the ends of the shaft. 100
- 25 10. An airship structure comprising a longitudinal shaft formed of a plurality of sections arranged end to end; means forming flexible joint connections between the shaft sections; a plurality of hoop members spaced along said shaft and encircling it; means extending between each hoop member and the shaft to support the shaft within the hoop members; and longitudinally resilient tension means connected to the shaft and to the said shaft-supporting means of each hoop and adapted to exert a tension upon the shaft sections longitudinally and outwardly, whereby the shaft sections are held yieldingly pressed together and the shaft is yieldingly held against buckling. 110
- 30 11. An airship structure comprising a longitudinal shaft formed of sections arranged end to end; means forming flexible joint connections between the shaft sections; a plurality of hoop members spaced along said shaft and encircling it; means extending between each hoop and the shaft to support the shaft within the hoop; and longitudinally resilient tension means connected to the shaft and to the said shaft-supporting means of each hoop and adapted to exert a tension upon the shaft sections longitudinally and outwardly, whereby the shaft sections are held yieldingly pressed together and the shaft is yieldingly held against buckling. 120
- 35 12. An airship structure comprising a longitudinal shaft; a plurality of hoop members spaced along said shaft and encircling it, said hoop members being each formed of a plurality of sections arranged end to end and flexibly connected together; and longitudinally resilient tension members connected to the hoop sections and to the shaft and adapted to exert an inward tension upon the said sections and hold them yieldably pressed together. 130
- 40 13. An airship structure comprising a longitudinal central shaft formed of sections arranged end to end; means forming flexible joint connections between the shaft sections; a plurality of hoop members spaced along said shaft and encircling said joint connections, said hoop members being each formed of a plurality of sections arranged end to end; means forming flexible joint connections between said hoop sections; a series of longitudinally resilient tension strands arranged radially around each joint connection and connecting it to the encircling hoop; longitudinally resilient tension strands arranged around the shaft and extending diagonally outwardly therefrom and connecting each shaft joint with the said radial strands leading from the next adjacent joints at either side; longitudinally resilient tension strands arranged longitudinally and connecting the different hoop members to each other and to the shaft ends, said longitudinal strands being connected to the hoop members at points spaced around them; and a plurality of gas bags each arranged inwardly of the said longitudinal strands between each pair of hoop members and formed to extend around the said diagonal strands, the ends of each bag being 140

located below the shaft and spaced apart, whereby a longitudinal corridor space will be formed below the shaft.

14. An airship structure comprising a longitudinal shaft; a plurality of hoop members encircling the shaft and spaced therealong; means extending between each hoop member and the shaft to support the shaft within the hoop members; means holding the peripheries of the hoops in spaced positions longitudinally of the shaft; and a plurality of gas bags each located between each pair of hoop members and formed to extend around the shaft, the ends of each bag being located below the shaft and spaced apart to form a gap, and the gaps of all the bags being in longitudinal alinement, whereby a longitudinal corridor space will be formed below the shaft.
15. An airship structure comprising a resiliently flexible longitudinal shaft, a plurality of resiliently flexible hoop members encircling the shaft and spaced therealong; longitudinally resilient tension members extending between each hoop and the shaft and supporting the shaft within the hoops; longitudinally extending and longitudinally resilient tension members connecting the hoops to each other and to the shaft to yieldingly hold the hoops in spaced position longitudinally of the shaft; and a plurality of gas bags each located between each pair of hoops inwardly of said longitudinal tension members and formed to extend around the shaft, the ends of each bag being spaced apart below the shaft to form a gap and the gaps of the different bags being in longitudinal alinement to form a longitudinal corridor space below the shaft.
16. An airship structure comprising a longitudinal shaft; a plurality of hoop members encircling said shaft and spaced along it; means yieldably supporting the shaft within the hoop members; and longitudinally extending tension members connecting the hoop members to each other and to the ends of the shaft, the said tension members being connected to the hoop members at point spaced therearound and being longitudinally resilient.
17. An airship structure comprising a longitudinal shaft; a plurality of hoop members encircling said shaft and spaced therealong; a plurality of transverse tension members connecting each hoop member at points spaced therearound to the shaft and adapted to support the shaft within the hoop members, said transverse tension members tending to contract the hoop members; inner longitudinal tension members connected to the shaft at points spaced around it and adapted to exert a stress upon the shaft tending to compress it longitudinally; and outer longitudinal tension members connecting the hoop members to each other and to the ends

of the shaft said outer tension members being connected to the hoop members at points spaced around them.

18. An airship structure comprising a longitudinal shaft; a plurality of annular members encircling said shaft and spaced along it; means supporting said shaft within said annular members; and tension members arranged around the shaft and connected to it at points spaced therealong, said tension members being adapted to exert a tension upon the shaft both longitudinally and outwardly thereof at all sides tending to resist buckling of the shaft.

19. An airship frame comprising a longitudinal shaft formed of a plurality of sections arranged end to end and flexibly connected together; a structure surrounding said shaft and adapted to hold the outer envelope of the airship distended; and longitudinally resilient tension members arranged around the shaft and connecting each shaft section to said surrounding structure, said tension members being adapted to exert a tension upon the shaft both longitudinally and outwardly thereof at all sides tending to hold the shaft sections together and to resist bending of the shaft.

20. In an airship, the combination of a yieldable resilient frame structure; an outer envelope covering said frame structure and formed with overlapping portions adapted to render the envelope extensible; and resilient tension means adapted to yieldably resist the extension of the envelope.

21. In an airship, the combination of a yieldable resilient frame structure; an outer envelope covering said frame structure and formed with overlapping portions extending transversely around the frame structure at longitudinally spaced points and adapted to render the envelope extensible; and resilient tension means adapted to yieldably resist the extension of the envelope.

22. In an airship, the combination of a yieldable resilient frame structure; an outer envelope covering said frame structure and formed with longitudinally overlapping folds extending transversely around the envelope at points spaced along its length, the said folds being adapted to render the envelope longitudinally extensible; and tension springs connected to each of said folds at points spaced around the envelope and adapted to yieldably resist the extension of the envelope.

23. An elongated airship frame comprising a plurality of outer members extending transversely around the longitudinal axis of the airship and formed and arranged to give shape to it; and resilient means adapted to yieldably hold said members against movement relatively to each other and relatively to said axis, said resilient means being adapted to permit the outer members to be

displaced both transversely and longitudinally with relation to the axis to cushion an impact received from any direction, and being adapted to restore said members to their normal positions when they are relieved of pressure.

24. In an airship, the combination of an elongated internal frame structure formed and arranged to give the ship shape and strength; means to render said structure transversely resilient whereby it will yield transversely under wind impact; and an extensible envelope enclosing said frame structure, said envelope being extensible to permit it to accommodate itself to the flexing of the enclosed frame structure without rupture.

25. In an airship, the combination of an elongated internal frame structure extending from end to end of the ship and formed and arranged to give the ship shape and strength; means to render said structure transversely resilient whereby it will yield transversely under wind impact; and an envelope enclosing said frame structure.

26. In an airship, the combination of an

elongated internal frame structure formed and arranged to give the ship shape and strength and comprising a central longitudinally extending member rigid to resist compression strains and provided with means to render it transversely resilient; and surrounding frame members formed and arranged to give shape and strength to the ship and provided with means to render the ship frame structure longitudinally resilient at the periphery of the ship.

27. In an airship, the combination of an elongated internal frame structure formed and arranged to give the ship shape and strength and comprising a central longitudinally extending member; and surrounding frame members connected to the central member and formed and arranged to give shape and strength to the ship and provided with means to render the ship frame structure longitudinally resilient at the periphery of the ship and transversely resilient to yield under wind impact.

In testimony whereof I hereunto affix my signature.

FERNAND E. d'HUMY.
